SOUNDPROOF SHIELD

Pierre A. Lienard, Clamart, France, assignor to
 Office National d'Etudes et de Recherches Aero-
 nautiques, Chatillon sous Bagnoux, France,
 a company of France

Application May 19, 1951, Serial No. 227,136

3 Claims. (Cl. 128—152)

1

This invention relates to soundproof shields or helmets intended to be worn over the ears of a subject as protection against noise and as an aid to telephonic communication, and more particularly to a noise shield constructed of a plurality of laminations of metallic and non-metallic materials having widely different mechanical properties offering a maximum of protection against ambient noise.

Soundproof shields for the ears are known in which cups or shells of soft and flexible materials such as rubber are provided to fit over the ears of the wearer, with or without accommodation for the receivers of a telephone headset. These known devices however provide only an imperfect degree of soundproofing because, being made of materials of low and substantially uniform modulus of elasticity, they transmit sound waves without great attenuation, especially at low frequencies.

According to the present invention instead, there is provided a shield which combines into a unitary structure a plurality of layers of metallic and non-metallic materials, having high coefficients of internal friction and having widely dissimilar moduli of elasticity. By the selection of materials having these properties and by their intimate union into a unitary structure, the transmission of sound from the exterior to the interior of the shield is greatly reduced as regards both the propagation of sound waves through the structure of the shield and as regards sympathetic vibrations of the structure or of the various elements thereof as a whole.

According to another feature of the invention the various layers or laminations of the shield, and in particular the metallic layer or layers thereof, are given a shape which permits the ready conformation of the shield to the head of the wearer or to the heads of successive wearers, so as to effect an improved seal between the shield and the wearer's head in spite of the use of metallic layers as elements of the shield.

The invention will now be further described in detail in terms of a preferred embodiment and with reference to the accompanying drawings in which

Fig. 1 is a view partly in section of a soundproof shield according to the invention incorporating a telephone receiver;

Fig. 2 is a graph illustrating the sound absorption occurring in the layers of the soundproof shield of the invention;

Fig. 3 is a sectional view, at a reduced scale, of an insert adapted to replace the telephone re-

2

ceiver shown in the shield of Fig. 1 when the shield is to be used otherwise than for communication purposes;

Fig. 4 is a view in plan of a spacer adapted for use with the shield of the invention when employed by a user wearing spectacles, and

Fig. 5 is a sectional view taken on the line 5—5 of Fig. 4.

The shields of the invention are used in pairs, one for each ear of the wearer, and they may be used with or without the receivers of a telephone headset. Fig. 1 shows a sectional view of one such shield in which a telephone receiver has been fitted. The shield of Fig. 1 is of a size to surround completely the external ear, preferably without touching it, and is adapted to seal off the auricular canal from exterior space and to protect from acoustic vibrations the portion of the head most sensitive to bone conduction. The two shields are connected together for use by means of a headband, not shown, which may be of any suitable type and to which the shields may be connected by means of forks 7 and thumb screws 8.

The shield of Fig. 1 comprises a laminated structure of which the major component, in volume, is a lightweight plastic material having a high coefficient of internal friction, for example polyvinyl chloride foam. Polyvinyl chloride is to be preferred to rubber foam which has too low a mechanical hysteresis. A cup or shell 1 of such plastic material is joined in intimate contact as by gluing with a cup-shaped sheet 3 of lead or of a lead-tin alloy. A second shell or lamination 2 of plastic material similar to the shell 1 engages the inner side of the metallic sheet 3 in similar intimate contact. The shell 1 is encased in a metallic cup 5, made for example of aluminum, which serves both acoustic and mechanical purposes for the shield. The cup 5 provides mechanical protection to the shield as a whole and provides also with the plastic shell 1 an additional interface between dissimilar materials at which a fraction of the incident sound waves are reflected.

With the four laminations 1, 2, 3 and 5 the sound must pass through substantially the entire surface of the shield and pass through four separate layers of material with three plastic-metal interfaces in order to penetrate into the interior. This produces a great attenuation of incident sounds even as to low frequency components. At each of these interfaces the discontinuity in medium effects reflection of a portion of the incident sound wave amplitude.

The construction of the invention provides a further reduction in acoustic transmission to the interior of the shield by the intimate union of the plastic layers 1 and 2 with metallic layers 3 and 5. By affixing the plastic layers to the cup 5 and to the lead alloy sheet 3 there is promoted a loss of energy in friction attendant upon the mass vibration of the metallic layers when vibrating as diaphragms. By increasing the damping of these vibrations the points of resonance of the metallic laminations are substantially lowered. According to the invention therefore the damping of vibrations of the outer casing 5 and of the intermediate metallic sheet 3 is increased by gluing or otherwise fastening thereto in intimate contact the layers of plastic foam material 1 and 2 which have, for their density, a high internal coefficient of friction or acoustic resistivity.

Attenuation of sound waves passing through the resulting structure is therefore due not only to the alternation of materials having widely different moduli of elasticity but also to dissipation of sonic energy by internal friction in the plastic layers and also to the damping which these plastic layers provide to vibration of the metallic layers 3 and 5.

Apart from the leakage of sound past the edge of the shield where it adjoins the skin of the wearer, which is reduced to a minimum by the shape given to the edge of the shield of the invention, as will be presently described, the acoustic permeability of the shield depends upon three factors, viz. the coefficients of internal friction or the acoustic resistivities of the component layers, the coefficients of transmission of the sound waves across the various interfaces between the successive layers of the shield, and the transmission factors representing the flexural vibrations of the laminae as diaphragms.

The coefficient of transmission for sound waves progressively propagated across an interface between two different media is given by

$$\frac{4m}{(1+m)^2}$$

in which

$$m = \frac{\sqrt{E_2 \rho_2}}{\sqrt{E_1 \rho_1}}$$

is the ratio of the acoustic resistivities of the media, E_1 and E_2 are their bulk moduli of elasticity and ρ_1 and ρ_2 are their densities. The following table gives values for the coefficients of transmission through aluminum-rubber foam, rubber foam-lead, and lead-rubber foam interfaces.

Material	E , in dynes/cm. ²	ρ , in grams/cm. ³	m	$\frac{4m}{(1+m)^2}$
aluminum...	21×10^{10}	2.7	7.5×10^5	1×10^{-3}
rubber foam...	54×10^5	.1	7.4×10^2	
lead-----	6×10^{10}	11.3	8.2×10^5	1.1×10^3
rubber foam...	54×10^5	.1	7.4×10^2	0.9×10^{-3}

Substantially the same coefficients of transmission as those of the table apply when foam rubber is replaced by polyvinyl chloride foam, the latter having as modulus of elasticity 150×10^5 dynes per cm.² and as density .035 grams/cm.³ and consequently an acoustic resistivity of 7.3×10^2 grams per sec. cm.², substantially equal to that of rubber foam.

The data of the table show that by choice of media on either side of the interfaces having widely dissimilar moduli of elasticity the ratios m of the acoustic resistivities of the two media at the interfaces are made either very large or very small by comparison with unity so that in either case the resulting coefficient of transmission is very small.

The "diaphragm" transmission coefficient is without practical importance in the case of the plastic layers because of their large thickness compared to their diameter. In the case of the metallic layers 3 and 5 the effective diaphragm transmission coefficient is greatly reduced by the damping of these layers which are loaded with the plastic layers 1 and 2. Apart from the loading factor, the diaphragm transmission coefficient decreases with increasing mass of the lamina undergoing flexural vibrations and with its internal coefficient of friction. In order to reduce this transmission coefficient it is therefore advantageous to use for the metallic layers metals having at once a high density and a high coefficient of friction. Lead fulfills both of these requirements and is therefore used in the shield of the invention at the interface between the two plastic layers. The internal coefficient of friction of a material may be measured by the loss of energy per vibration cycle of a bar subjected to transverse vibrations. The curves of Fig. 2 give in logarithmic coordinates the loss in ergs of energy per cycle and per unit volume of the preferred materials of the shield of the invention, as a function of the amplitude of vibration in microns. The curve 51 applies to lead, curve 52 to polyvinyl chloride foam, curve 53 to foam rubber and curve 54 to aluminum, all for vibrations between 100 and 200 cycles per second. At a vibration amplitude of four microns the losses for lead, polyvinyl chloride foam and rubber foam are respectively $3, 3 \times 10^{-2}$ and 1.2×10^{-3} ergs. It is apparent from Fig. 2 that lead is highly effective in sound absorption and that polyvinyl chloride foam is much more so than foam rubber.

Referring again to Fig. 1, except for the outer protective layer 5 each of the laminations is provided with a broad margin extending laterally in a direction substantially parallel with the surface of the wearer's head against which the shield is to be applied. By so shaping the laminations a broad annular area of contact is made available over which an effective seal may be made to exclude the passage of sounds under the edge of the shield. The metallic layer 3 in particular is formed with a flaring border or flange 4 which because of its malleable nature may be readily conformed by each wearer to the shape of his own head. On either side of the flange 4 the plastic layers 1 and 2 are formed with parallel flanges 13 and 6. With the flange 4 the flanges 18 and 6 form a pliable border which can be given a permanent set in accordance with the shape of the wearer's head, insuring a substantially perfect seal. This annular area of the shield is covered over with a fibrous material 11 which improves the acoustical seal and the acceptability of the shield to the wearer.

Within the cavity formed by the cup-shaped conformation of the laminations, space is provided for the accommodation of a telephone receiver 9. The receiver may be positioned within the cavity in an optimum position with respect to the ear. One preferred form of receiver is

provided with a hollow rim 10, of soft rubber circumferentially perforated, which may be filled with cotton or other absorbent material. The cavity is circumferentially lined about the receiver 9 with absorbent material such as cotton which may be retained in position by a sack or pocket 12. The sack may further include a desiccant. The irregularly limited space thus enclosed between the head of the wearer, the external ear, the surface of the absorbing pocket 12 and the reentrant surface of the receiver 9 promotes the absorption of such sounds as may penetrate the shield and retards the appearance of cavity resonances and reverberations which produce irregularities in the wearer's capacity to hear.

If it is unnecessary to provide the wearer with facilities for telephonic communication, the receiver 9 may be replaced with an insert 13 (Fig. 3) having the same exterior shape and preferably manufactured of a plastic foam material similar to that employed for the shield layers 1 and 2. The insert is hollow and may be filled with an absorbent material maintained in place by a grating 14.

The invention provides for use with the shield a spacer 15 illustrated in Figs. 4 and 5 which serves to preserve the soundproof qualities of the shield for users who wear glasses. The spacers 15, one for each of the two shields employed, may be made of rubber or of any similar flexible and pliable material and are of generally meniscus section as illustrated in Fig. 5. By virtue of this shape they fit on their concave sides over the malar bones and under the ring of fabric 11 at the annular edge of the shield. The spacers are provided with groove 17 in order to accommodate the limbs of the wearer's eyeglasses.

While the drawings and description herein have set forth in detail the construction of a preferred embodiment of my invention, various modifications may be made within the scope of the invention, as set forth in the appended claims.

I claim:

1. A noise shield for the human ear comprising an aluminum cup, a first cup-shaped member of polyvinyl chloride foam adapted to fit within the aluminum cup and having a flaring brim extending beyond the cup, a continuous thin lead-bearing metallic membrane fitting within the first polyvinyl chloride member and glued thereto, a second cup-shaped member of polyvinyl chloride foam adapted to fit within the membrane and over the outer ear, and an annular sack of sound absorbent material supported within the second polyvinyl chloride member.
- 15 2. An ear shield comprising an outer metallic cover, a first flanged cup-shaped member of aerated plastic material fitting exclusively of its flange within said cover, a flanged sheet of metal of high density fitting within said first member, a second flanged cup-shaped member of aerated plastic material fitting within said sheet, and means to bond said sheet to each of said members.
- 20 3. An ear protector comprising a metallic cover, two flanged cup-shaped members of non-metallic material of low modulus of elasticity and low density, a flanged metallic cup of high density fitting between said members, and means to join the surfaces of said cup in intimate union to the adjacent surfaces of said members.
